2 SHEETS—SHEET 2.

FIG. 3

UNITED STATES PATENT OFFICE.

JOUZAS KARASEVICZ, OF SOUTH AMBOY, NEW JERSEY.

LOCK.

1,336,080.

Specification of Letters Patent.

Patented Apr. 6, 1920.

Application filed May 29, 1919. Serial No. 300,666.

To all whom it may concern:

Be it known that I, JOUZAS KARASEVICZ, a citizen of Russia, residing at 238 Peltus St., So. Amboy, county of Middlesex, and State of New Jersey, have invented certain new and useful Improvements in Locks, of which the following is a specification:

This invention has as its object the provision of a lock adapted to be applied to ordinary hinged doors whereby they may be secured in position.

A further object is to provide a latch bolt capable of being locked when in an extended position, against movement by the ordinary handles.

A still further object is to provide a lock which may be operated from either side of the door by a special key, the lock bolt being held when in an extended position against pressure applied to the end of the same.

These and other objects are attained by the novel construction and combination of parts hereinafter described and shown in the accompanying drawings, forming a material part of this disclosure and in which—

Figure 1 is a longitudinal sectional view taken on line 1—1 of Fig. 4.

Fig. 2 is a similar longitudinal sectional view taken on line 2—2 of Fig. 3.

Fig. 3 is a transverse view taken on line 3—3 of Fig. 2.

Fig. 4 is a similar longitudinal sectional view taken on line 4—4 of Fig. 1, and

Fig. 5 is a longitudinal sectional view taken through the knobs used to operate the latch bolt.

Referring to the drawings in detail, the numeral 10 indicates the lock casing, having an opening near one end from which projects the latch bolt 11, having a beveled surface 12. The stem 13 of the latch bolt is cylindrical and formed in it is an elongated slot 14, through which passes a pin 15, set in the lock casing.

Abutting against the pin 15 and latch bolt 11 are the coils of a compression spring 16, adapted to normally project the bolt outwardly.

Formed at the inner end of the stem is a transverse, bar-like member 17, carrying pivots 18, one end of the bar projecting to some distance beyond the pivot. These

pivots are engaged in slots 20, formed in the ends of links 21, pivoted on pins 22 to 55 the oppositely disposed angular arms 23, of an actuating lever having a hub 24, the extending ends 25 of which are journaled in the opposite sides of the lock casing 10, the hub having a rectangular aperture 26, 60 receptive of a square bar 27, having at one end a hub 28 of a knob 29, held by the screw 36, an oppositely disposed knob 30 being secured at the opposite end of the bar by a pin 31 set in the outer end of a lever 32 65 contained in a recess in the bar 27, and normally pressed outward by a flat spring 33, a plurality of holes being formed in the hub 35 of the knob so that it may be adjusted at different distances upon the bar 70 27. Thus it will be seen that upon turning either of the knobs the lever 23 will be actuated and the latch bolt 11 retracted within the casing.

Fixed upon the end wall of the casing is 75 a plate 38 containing a slot in which operates a pin 39, having an actuating extending head 40 the pin being adapted to make contact with a spring element 41, formed with a flat base 42, having a loop 43, and 80 outwardly turned terminal 44, which, when the pin 39 is pressed outwardly in the slot, in the direction of the latch bolt, intercepts the extension 19 of the bar 17, thereby preventing the latch bolt from being retracted, 85 thus forming one element of the lock.

A lock bolt having an extending head 50, formed with a bar 51, is slidably engaged within the lock casing, and guided at its inner end between a pair of raised projections 52 so as to cause the lock bolt to move in a straight line.

Formed upon one of the side edges of the lock bar 51 are a pair of lugs 53 having between them a recess 54 adapted to receive a 95 block 55 pressed normally therein by the end of a flat spring 56, the spring being coiled about a pivot 57, set in the wall of the casing, the block 55 engaging between the lugs when the bolt is extended to its extreme limit of movement.

The block 55 is formed upon a plate 58 pivoted on the pin 47 and freely, movable below the lock bar 51, opposite its edge extending so that when a key is entered, the 105 plate may be forced rearwardly, moving

the block 55 out of engagement with the lugs and permitting the lock bolt to be moved in either direction.

Extending from the side of the lock bar 51, opposite to the lugs 53, are pairs of spaced projections 59 and 60 for purposes which will be further on disclosed.

Formed upon opposite sides of the lock casing are cylindrical extensions 62, opposite to which are the key entrances 63, receptive of a peculiar key, indicated generally by the numeral 64, which upon being entered engages central stems 65, formed with the screws 66, entering the cap portions of the extension 62, and which are surrounded by the coils of springs 67, these springs pressing against the cap portions at one end and with sleeves 68 at their outer ends, the sleeves having flanges 69 through which the bolts 66 pass.

These sleeves are rotatable within the recesses 70 formed in the extensions and are provided with oppositely disposed lugs 71 movable in recesses 72, when pressed in by the key, so as to pass the extending flanged edges 73, which are formed level with the interior of the lock casing.

Also extending from the flanges 69 are a pair of opposed conical pins 75 which enter into corresponding openings formed in the head of the key so as to cause the sleeve to be rotated, the enveloping portion of the key making contact between the projections 59 or 60 of the locks bar 51, after first having displaced the plate 58, thereby permitting the lock bolt to be moved in the ordinary manner.

From the foregoing it will be seen that a key may be entered from either side of the

door and engage with either the projections 40 59 or 60 of the lock bolt whereby the desired result may be obtained.

Having thus described my invention what I claim as new and desire to secure by Letters Patent, is—

1. In a lock, the combination with a casing, a latch bolt and a lock bolt operable therein, of a stem on said latch bolt, a spring surrounding said latch stem, a transverse bar formed with said stem, slotted links engaging with the ends of said bar, a double armed lever pivoted to said links, knobs extending from each side of said casing, adapted to actuate said lever, a detent spring secured in the casing of said lock, 50 said detent spring being engageable with said transverse bar whereby it is held when in an extended position, and means for releasing said detent spring so that the latch bolt may be operated by said knobs.

2. In a lock, the combination with a casing, a lock bolt slidably engaged transversely thereof, and means for holding said lock bolt in either of its positions, of a pair of cylindrical extensions formed upon opposite sides of said casing, sleeves rotatable therein, means for normally preventing the rotation of said sleeves, and a key adapted to press said sleeves inward for allowing rotation of said sleeves, said sleeves normally 65 preventing rotation of said key and said key adapted to release said holding means to operate the bolt and the wards of said key engaging with the projections of said lock bolt whereby it may be operated.

In testimony whereof I have affixed my signature.

JOUZAS KARASEVICZ.
